UNITED STATES PATENT OFFICE.

WILLIAM MERRSCHAFT, OF NEW YORK, N. Y.

DISPLAY SIGN.

Application filed November 5, 1926. Serial No. 148,400.

My present invention relates to luminous display signs employed for advertising and has a preferred application to signs of the type used in display rooms and store windows, and not exposed to external weather conditions.

Among the objects of the invention are to provide a display sign of low cost and rugged construction, which can be easily 10 and expeditiously made up without the use of any tools whatsoever, to provide at will any reading matter or color effect desired, and which, in use, produces a strikingly attractive and luxurious effect with a minimum consumption of electric power.

Another object is to provide replaceable translucent character units especially useful in a sign of the character set forth, but applicable to other uses, which shall, though 20 of very little cost, produce the effect, in service, of solid slabs of polished illuminated glass, marble or amber.

The objects may be accomplished in a display sign with a frame affording windows for positioning replaceable translucent character units, preferably locked in place by an appropriate backing, which may include means for carrying colored gelatin or paper strips, to modify the transmitted 25 light. In a preferred specific embodiment, the character frame is a sheet metal grid presenting rows or tiers of window apertures, and the backing is a plate hinged thereto and provided with corresponding 30 windows. Each of the character units has a holding portion protruding laterally therefrom, which is securely clamped in place between the slats of the character frame and of the backing plate, that define 35 the respective window openings thereof. The desired effect of the solid slabs of glass, marble or amber may be produced in the character units by forming the same of tray 40 shape, hollow in the interior, preferably of paraffin paper, such as is employed for paper 45 drinking cups, and having the symbol thereon imprinted in an opaque pigment. The securing means for the character unit is preferably a rim formed as an integral 50 part of the tray.

In the preferred application of the invention, the sign structure is used with the specific character units set forth, the rim of each character tray being securely clamped 55 between the slats defining the windows of the character plate and of the backing plate.

The connection is, therefore, light-tight, so that the illumination will emanate only through the material of the tray shaped character.

In the accompanying drawings in which is shown one of various possible embodiments of the several features of this invention,

Fig. 1 is a front view of the sign, 65

Fig. 2 is a transverse sectional view taken on the line 2-2 of Fig. 1, showing the display cover in open position,

Fig. 3 is a sectional view on a larger scale taken on the line 3-3 of Fig. 1, 70

Fig. 4 is a perspective view indicating the sign in the process of making the same up,

Fig. 5 is a perspective view of the exterior of one of the characters,

Fig. 6 is a view similar to Fig. 5 showing 75 the character viewed from the interior, and;

Fig. 7 is a fragmentary vertical section of a modification.

Referring now to the drawings, I have shown a display sign comprising a casing 80 of more or less conventional construction including a narrow rear wall 10, diverging lateral walls 11 and correspondingly trapezoidal top and bottom walls 12 provided with ventilating apertures 13 for the escape 85 of the warm air generated by the lamp bulb 14, which may be mounted in an ordinary conventional type of electric flasher socket 15. The inner surfaces of the various walls are preferably reflectors. At the front of 90 the casing and to the rim of the lower edge thereof as at 16, there is preferably hinged the frame 17 of the luminous cover, carrying the readable matter of the sign. This frame is preferably secured in closed position by means of a wing nut 18 secured by a screw 19 at the rear of the upper rail 17 of the frame, and coacting with an upstanding flange 20 on the top 12 of the case.

The cover frame 17 presents an open construction, the lower part of which is provided with a unitary sheet metal support or frame 21 for the luminous characters. Illustratively, the character frame 21 is provided with four rows of rectangular openings 22, in each of which a unit of the character shown in Figs. 5 and 6 is retained.

I have shown a longitudinal sheet metal strip 23 which may be soldered or otherwise 110 secured to the upper edge of the character frame and serves to hold in position the

lower edge of a rectangular glass panel 24, the upper edge of which is retained within a longitudinal sheet metal strip 25 secured to the upper rail 17^a of the frame. In back 5 of the window panel, will be mounted a translucent paper sheet 26 affording a title legend 27 for the sign.

The individual character elements, 10 placeably disposed within the windows 22 are provided with parts by which they can be secured in position, preferably between the character frame and a separate backing plate 28. The backing plate 28 as shown, is preferably hinged at 29 near the bottom of 15 the character frame 21 and includes windows 30 of the same size, shape and arrangement as those of the character frame and registering therewith when the backing plate is moved to closed position. Illustratively, 20 a removable longitudinal lock strip 31 interlocks with the downturned upper edge 32 of the backing plate and with the rear rail of the window supporting strip 23. This lock rail extends preferably the entire length 25 of the sign and has an outstanding rectangular handle portion 33 by which it can be easily shifted for application and removal thereof.

The backing plate has longitudinal holding 30 strips 34 soldered thereto, which serve to mount preferably translucent colored strips 35 of gelatin or paper, that may be placeably held in back of the windows. Vertical rods 36 are soldered in position at the 35 various rails of said backing plate at the rear thereof and serve to stiffen the construction and also to retain the gelatin strips against curling out of place, due to the heat of the lamp.

40 A preferred character unit is shown in Figs. 5 and 6. It comprises simply a rectangular element of ordinary paper of the grade commonly used for paper drinking cups stamped into a rectangular tray shape, 45 as shown, and including, in particular, a rectangular face 37, integral upstanding side walls 38 and end wall 39, and preferably an integral rectangular flange 40 extending outward from the end and side walls. The excess material is gathered in, to form crinkles 50 41 at the corners of the tray and the flange rim, which serve, moreover, to stiffen the tray. The symbol 42 is preferably printed or painted with an opaque pigment both on 55 the exterior and interior face of the tray base. The tray after being formed preferably by a die, is impregnated in a bath of paraffin and then allowed to dry.

60 The spaces between words are formed by trays similar to that described, but rendered completely opaque throughout the entire surface thereof, one of said spacer units being shown at 43.

65 It will be understood that in making up any particular sign, the selected character

units or trays are laid into the corresponding open windows 22 of the front plate or character frame 21, which, for this purpose, is laid down in horizontal position, as shown in Fig. 4, whereupon the hinged backing 70 plate 28 is tilted downward and locked in position by applying the lock strip 31. Thereupon, the cover 17 is raised and held closed by means of the wing nut 18. It will be seen that each of the characters is 75 securely clamped in position at its border flange 40 between the slats making up the contour of the corresponding windows in the character plate 21 and the corresponding slats of the backing plate. The character 80 plate positions the character units and the backing plate locks them in place.

As best shown in Fig. 3, the rims 40 of the character trays are so securely clamped between the slats of the character frame 21 and those of the backing plate 28 that no light will escape around the rims of said trays. The light, colored by the gelatin strips, is transmitted only through the face 37 and the side and end walls of the trays, producing 90 the rich three dimensional effect of thick solid, illuminated colored, frosted glass, or of marble or amber, rigidly secured in corresponding bezels and protruding outward therefrom. The light emanates not only 95 from the face but also from the side and end walls of the character units.

The character units though of trifling cost 100 are not brittle as glass; they are form sustaining and not subject to injury by handling or by heat due to the lamp. The tray units not in use can be kept in nested stacks, 105 since their side and end walls flare as shown, without danger of marring by abrasion or adhesion.

While the character units are preferably made in the specific manner described, it will be understood that it would be within the scope of my invention, in its broader aspect, to press the same directly from paper pulp. It would also be within the scope of the invention to substitute for paper, other fabrics, such as vellum, oil cloth, thin leather and the like. 110

While I prefer to form the holding rim of the character unit as an integral part of the character block or panel, it is within the scope of the invention to provide separate and distinct holding clips or other attaching means for the character units. 115

In Fig. 7 is shown an alternative embodiment for locking the backing plate 28' in position. The various parts of Fig. 7 are substantially identical with those of Fig. 3 and corresponding parts are designated by the same reference numerals primed. In this connection, however, I have shown in lieu of the lock strip 31 extending longitudinally of the backing plate a transverse locking rod 50. This rod has an upturned handle 125 130

end 51 and is passed through a pair of loops or staples 52 and 53, one at the lower channel of the window 24' and the other at the base of the frame. The rod 50 of which several may be used, when placed in position as shown reacts against the various channels or runners 34' on the backing frame and effectively prevents buckling of the same. When it is desired to replace the characters, the rods 50 are simply withdrawn and the backing plate is released. The handle 51 may be turned flat against the window when the parts are assembled.

It will thus be seen that there is herein described an apparatus in which the several features of this invention are embodied, and which apparatus in its action attains the various objects of the invention and is well suited to meet the requirements of practical use.

As many changes could be made in the above construction, and many apparently widely different embodiments of this invention could be made without departing from the scope thereof, it is intended that all matter contained in the above description or shown in the accompanying drawings, shall be interpreted as illustrative and not in a limiting sense.

Having thus described my invention, what I claim as new and desire to secure by Letters-Patent of the United States is:—

1. An illuminated display sign comprising a casing having a front cover plate provided with tiers of rectangular apertures therein, translucent rectangular character carrying devices protruding forward through the apertures to form words or sentences, and each provided with a rim extending in back of the front plate, and a backing plate, means releasably securing said backing plate in position against said front plate to secure the rims of said character carrying devices in position.

2. An illuminated display sign having a cover provided with a grille of rectangular windows, rectangular translucent character carrying devices removably positioned in said windows to form words or sentences, each provided with a flange extending in back of the plate, a backing plate structure having window apertures therein, translucent colored strips removably positioned relative to said backing structure to extend over said windows, said backing structure having solid metal parts to engage the rims of said character carrying devices and means to releasably secure said backing structure in engaging position.

3. An illuminated display sign comprising a casing having a source of light therein, a front cover having a grille of rectangular apertures therein, a backing plate having apertures therein to register with those of said cover plate when said backing plate is

brought against the latter, said two plates affording a clamping construction for securing in position translucent display characters for said windows.

4. A luminous display sign comprising a casing, a cover therefor having a grille of windows therein, translucent display characters mounted in position at said windows, a backing plate hinged at the lower edge of said cover, said backing plate having metal strips to extend along the window rims of said cover when elevated to operative position, and locking means retaining said backing plate in operative position, whereby translucent characters may be clamped in position between said cover and said backing plate at protruding portions thereof extending therebetween from beyond the rims of the windows.

5. An illuminated display sign comprising a casing having a source of light therein, a cover therefor, said cover having a metal frame provided with a grille of window openings therein for translucent characters, a backing plate hinged at the lower edge to the cover and having a grille of window apertures to register with those in the cover plate, said backing plate having holding strips for translucent colored panels, and locking means to retain the upper edge of the backing plate releasably in position against the cover.

6. A luminous display sign comprising a casing having a source of light therein, a display cover having a grille of rectangular windows therein for retaining translucent characters, a backing plate hinged to the lower edge of the cover plate and having a grille of windows therein to register with those of the cover when the backing plate is raised to closed position, a removable lock strip for retaining the backing plate locked against the cover, said backing plate having holding strips for retaining translucent colored sheets.

7. A character unit for a luminous display sign, said unit being tray-shaped to present a substantially block-shaped exterior, the face of said tray being light-transmitting in part and opaque in part to determine the symbol represented thereon, and means at the rim of the tray unit by which the latter is held in position in the sign.

8. A character unit for a luminous display sign, said unit being tray-shaped to present a substantially block-shaped exterior, the face of said tray being light-transmitting in part and opaque in part to determine the symbol represented thereon, and fastening means protruding outward from the rim of the tray and serving to hold the unit in position in a luminous display sign.

9. A character unit for a luminous display sign comprising a generally rectangular tray-shaped body of translucent material

having the symbol thereon in opaque pigment, said tray having fastening means unitary therewith and protruding outward therefrom for attachment of the unit in position.

10. A character unit for a luminous display sign, said unit comprising a tray-shaped element of form-retaining translucent sheet material, the face of said tray having the symbol thereof applied thereto in opaque pigment, the rim of said tray being bent outward to present means for retaining the character in position at the sign.

11. A character unit for a luminous display sign comprising a form retaining tray of translucent pressed sheet material the face of said tray having the symbol thereof applied thereto in opaque pigment, said tray having an outstanding flange at its rim by 20 which it may be secured in position in the sign.

12. A character unit for a luminous display sign, said unit comprising a flat panel of translucent non-friable material having 25 an opaque symbol thereon, and retaining means for said unit formed rigid therewith and extending outward to the rear of said panel beyond the periphery thereof.

13. A character unit for a luminous display sign comprising a form-retaining tray-shaped element of translucent fibrous material having the symbol in opaque pigment on the face thereof, said tray having holding means therefor rigid therewith and at the 35 rim thereof.

14. A character unit for a luminous display sign comprising a rectangular tray composed of impregnated paper fibre having the symbol thereon in opaque pigment, said tray 40 having at its rim, means for removably securing the same in position.

15. A character unit for a luminous display sign comprising a sheet paper tray having the material thereof krinkled to form the 45 corners or edges thereof, and having an integral outstanding rim, the symbol being depicted thereon with an opaque outline.

16. The method of forming a character element for a luminous display sign, which 50 consists in placing opaque characters on sheet paper, pressing the paper in a die into tray form, and impregnating with paraffin to produce a simulation of a solid slab of glass or similar material.

55. 17. An illuminated display sign comprising a casing having a source of light therein,

a cover therefor, said cover having a metal frame provided with a grille of window openings therein for translucent characters, a backing plate hinged at the lower edge of 60 the cover and having a grille of window apertures to register with those in the cover plate, locking rods extending at right angles to the hinged edge of the plate and staples for positioning the same in fixed position at 65 said cover above and below said backing plate, the length of said rods reacting against said backing plate and holding the same securely positioned against said cover plate.

18. An illuminated display sign comprising 70 a casing having a front cover plate provided with tiers of rectangular apertures therein, translucent rectangular character carrying devices protruding forward through the apertures to form words or sentences, 75 and each provided with a rim extending in back of the front plate, and a backing plate cooperating with the front plate, and means releasably securing said backing plate in position against said front plate to secure 80 the rims of said carrying devices in position.

19. An illuminated display sign comprising 85 a casing having a front cover plate provided with tiers of apertures therein, translucent character carrying devices protruding forward through the apertures to form words or sentences, and each provided with a rim extending in back of the front plate, and backing means cooperating with the front plate, and means releasably securing 90 said backing means in position against said front plate to secure the rims of said carrying devices in position.

20. A character unit for a luminous display sign comprising a form-retaining tray 95 shaped element of translucent fibrous material having a character in opaque pigment on the face thereof, said tray having at its rim, means for removably securing the same in position.

21. As an article of manufacture, a sign letter element produced from flexible material and comprising a front wall, side and end walls converging toward said front wall, a flange about the inner edges of said side and end walls, and a character delineated on the outer face of the front wall.

Signed at New York city in the county of New York and State of New York this 29th day of October, A. D. 1926.

WILLIAM HERRSCHAFT.
